(57) **CLAIM**

The ornamental design for a pillow, as shown and described.

DESCRIPTION

FIG. 1 is a front perspective view of a pillow;

FIG. 2 is a top plan view thereof;

FIG. 3 is a left side elevation view thereof; the right side elevation view being a mirror image thereof;

FIG. 4 is a bottom plan view thereof;

FIG. 5 is a front elevation view thereof; the rear elevation view being a mirror image thereof; and,

FIG. 6 is a front perspective view of a pillow showing our new design according to a second embodiment, the only difference between the first and second embodiments being the contrast in appearance of the panels on the right side and left side (not shown) in the second embodiment with respect to the other portions of the pillow. It being understood that all other surfaces are the same as those of the first embodiment shown in FIGS. 1–5. The stipple shading in FIG. 6 represents a contrast of appearance and does not represent any particular color, texture, or material.
